TELESCOPE RETICLE ADJUSTMENT

Charles H. Murr, Philadelphia, Pa., assignor to
the United States of America as represented by
the Secretary of War

Application March 16, 1950, Serial No. 150,068

5 Claims. (Cl. 33—50)

(Granted under Title 35, U. S. Code (1952),
sec. 266)

1

The invention described in the specification and claims may be manufactured and used by or for the Government for governmental purposes without the payment to me of any royalty thereon.

The present invention relates to telescope sights for use in connection with firearms, and has particular reference to the means employed for supporting the reticle within the telescope and adjusting the same for windage and elevation.

Broadly stated, the object of my invention is to provide a reticle holder which is capable of allowing the making of both vertical and horizontal adjustments of the reticle with respect to the axial center of the telescope, and which, by virtue of a unique pivoting action, tends constantly to urge the reticle in a direction midway between the conventional, mutually perpendicular horizontal and vertical adjusting screws so as to keep the reticle holder in constant abutment thereagainst.

A further object is to provide such a reticle holder which is simple and inexpensive to manufacture, easy to install within a telescope, and which will give trouble-free performance over long periods of constant use.

In the past, workers in the fire control field have recognized the need for a telescope gun sight that possesses mechanism for making fine and consistent adjustments of the reticle to correct for variations in windage and elevation and, at the same time, to be sufficiently rugged so as to be capable of withstanding the shock and vibration incident to the use of high velocity cartridges in guns with which telescope sights are usually employed. A number of such devices have been made in order to meet this requirement, such as those represented by U. S. Patents 2,180,184 issued to W. R. Weaver in 1939 and 2,189,766 issued to J. Unertl in February 1940. Although these examples of prior art devices suitably serve their purpose, the present invention has been found to possess certain additional advantages in attaining the aforementioned objects, and is therefore believed to be a desirable and valuable improvement to the art under discussion. This will be apparent from the following description which has reference to the accompanying drawings, wherein:

Fig. 1 is a view showing in dotted outline a conventional telescope mounted on a standard rifle, the reticle of the present invention being shown in top plan view as it is situated within the telescope;

Fig. 2 is a similar view of the reticle holder as same appears prior to placement thereof inside the telescope;

2

Fig. 3 is a sectional view through the flexible portion of the reticle holder taken from line 3—3 of Fig. 2;

Fig. 4 is a similar view from line 4—4 of Fig. 2;

5 Fig. 5 is a view taken along line 5—5 of Fig. 1 to show the manner in which the end of the reticle holder which contains the reticle proper is in constant abutment with the horizontal and vertical adjusting screws;

10 Fig. 6 is a longitudinal section through the telescope showing in full detail the relationship of the reticle holder to the interior of the telescope, and also the vertical or range adjusting screw;

15 Fig. 7 is a view taken along line 7—7 of Fig. 6 looking into the telescope from front to rear and showing the reticle holder so positioned that its reference line of sight passes through the axial center of the telescope;

20 Fig. 7A is a view similar to Fig. 7 except that the reference line of sight is shown displaced to the reader's left of the telescope's axial center;

Fig. 7B is similar to Fig. 7 except that the reference line of sight is shown displaced vertically above the axial center of the telescope; and

25 Fig. 7C is similar to Fig. 7 except that the reference line of sight is shown displaced to the reader's right of the axial center of the telescope.

In my improved construction, the telescope 11 is secured to the gun 12 in any conventionally suitable manner whereby the instrument will be held in substantially parallel relation to the gun barrel. The portion of the telescope within which my improved reticle holder is located comprises a hollow tube 13, as shown in Figs. 1 and 6, of varying diametral dimensions. Toward the objective or rear end of the telescope there is provided a right angled shoulder 14 which serves to limit the distance which the reticle holder can be moved forwardly toward the instrument's eyepiece, as will be made clear below.

The reticle holder proper, in the illustrative example, may suitably consist of three tubular overlapping and interfitting members including a support 16 (facing the scope's eyepiece, or the reader's right) for the reference sight marker 32, an intermediate portion 18, and a flexible, flared portion 19 which faces the reader's left, or the objective end of the telescope. The free end 22 of portion 19 is dimensioned to fit snugly within the encompassing telescope walls, but the remainder of the holder is of considerably lesser diameter than the telescope's interior. The reticle holder need not necessarily be made in this segmented fashion, or more segments may be utilized if desired as a matter of manufacturing

and assembling convenience. In the illustrated device, the three portions of the holder are secured to each other by any convenient means such as a number of rivets 21.

Flexible portion 19 is of a special construction whereby the objects of my present invention are achieved. It will be noted from Fig. 2 that, before the holder is inserted into the telescope, the free end 22 of portion 19 is bent at an angle to the longitudinal axis of the remaining portion of the holder. The remainder of portion 19 is made flexible by virtue of the illustrated staggered multi-slot construction. The material chosen for fabricating the holder may be of any suitable metal or other material which will permit limited flexure of the so-constructed holder portion, without causing it to lose its inherent tenacity to revert to its normal Fig. 2 shape.

In the extremity of free end 22 is a flange 23 which, when the holder is inserted into the telescope, as shown in Fig. 6, abuts against the scope's shoulder 14. In the periphery of flange 23 is a notch 37 (see Figs. 3-4) which mates with a pin 36 that projects from shoulder 14 on the inner wall of the telescope. This mating relationship serves to prevent relative rotation between the reticle holder and the telescope, and also serves to guide the holder into its proper position within the scope, as will be explained below. After the reticle holder is so installed it is then fixed against further axial movement with the further aid of a threaded ring clamp which is tightened against the free face of flange 23 as indicated at 24.

When so mounted, it will be noted that the free end 22 of the reticle holder portion 19 is rigidly confined by the encompassing interior walls of the telescope, as indicated at 26, so that this portion of the holder is in axial coincidence with the telescope. Since free end 22 is, however, constructed so as inherently to be angularly disposed with respect to the rest of the holder, the tendency is for the balance of the holder to be stressed in a direction that will restore the angular relationship. Thus, when the reticle holder is positioned within the telescope, advantage may be taken of this tendency by arranging to have holder portions 16-18-19 flex in a line which is originally midway between the positions of the telescope's mutually perpendicular, conventional reticle positioning screws 27-28. This is accomplished by proper placement of pin 36 and mating notch 37 so that when the holder is inserted into the telescope the holder will tend to flex only in that direction. Of course, as the holder is moved throughout its full range of adjustment it will not necessarily move along this same line, as the positioning screws will stress it away from that direction. However, the tendency to move back into the original path will always remain and this factor will serve to keep holder portion 16 in constant engagement with screws 27-28. Screw 27, which is turned by a knob 29, serves to move the reticle holder vertically and thereby provide for range adjustment. Screw 28, which is turned by knob 30, serves to move the reticle holder horizontally and thereby provide for windage adjustment. In Fig. 5 it may be seen that screws 27-28 are 90° apart and reticle holder portion 16 bears against those screws because of the reasons given above.

The flexure of holder portion 19 is so great that, if it were not for the pressure of screws

27-28, reticle holder portion 18 would make contact with the wall of the telescope at approximately the 45° mark between the two screws, because of the holder's inherent tendency to assume its normal shape as shown in Fig. 2. But, with free end 22 of portion 19 rigidly held by the telescope's wall, as at 26, and with screws 27-28 bearing equally against the periphery of holder portion 16 (as shown in Fig. 10) the effect is to compress the slot-like flexible holder portion 19 (as shown in Fig. 6), thereby to "straighten" and align the normally bent relationship of free end 22 with the rest of portion 19. Of course if screws 27-28 bear 15 unequally against holder portion 16, portions 16-18-19 will be flexed into correspondingly different positions with respect to the scope's axis, but in each position portion 16 would engage screws 27-28.

The need for stabilizing the reference sight support by forcing it continuously to bear against the range and windage adjustment screws 27-28 has long been well known. Previous solutions to this problem have generally involved the inclusion of resilient members such as springs which are installed at a third point on the telescope in contact with the periphery of the reference sight support, usually at about 135° radially of the axis of each supporting screw. However, the present invention eliminates the need for such additional stabilizing means, as the holder is so constructed that without such added support it will at all times, after being properly mounted within the telescope, retain the desired stability. 35 In addition, the slot-like construction of holder portion 19 serves further to cushion the holder against shock which may be transmitted both axially and transversely of the telescope upon firing the gun. However, it is to be understood that this and the other obvious advantages of the present invention are not necessarily limited to devices having the particular construction shown, for other suitable means may obviously be employed to attain the same unique flexible 40 action.

Illustrative of the manner in which the present invention works, there has been shown in Figs. 7 to 7C, inclusive, a series of different positions of the reticle holder. In Fig. 7, the holder's portion 16 has been forced down to the bottom of the telescope, as seen by the reader, but the reference sight or marker 32, which may be a pin or other suitable means, is shown passing through the axial center 34 of the holder. 50 In Fig. 7A, holder support portion 16 has been moved to the reader's left so that reference marker 32 is shown to the left of dead center. In Fig. 7B, support 16 has been moved to the maximum upward position and thus is above the center point. Finally, in Fig. 7C, support 16 has been moved as far as possible to the reader's right and marker 32 is there shown as being off to the right of center 34. Thus, it will be seen that the reference sight in my novel holder can be moved in a complete circle, thereby making possible a greater range of adjustability than was heretofore possible.

It will be apparent from the foregoing description and accompanying illustrations that an improvement has been made in the art of telescope reticle adjustments which is greatly simplified from point of view of manufacture and installation, and is unusually inexpensive and efficient. The said invention may of course be employed in

numerous embodiments as was indicated above, and therefore it should be understood that it is to be limited only by the scope of the appended claims.

I claim:

1. In a telescope comprising a tubular body and a reticle support therein, means for adjustably mounting said reticle support in operative position, comprising: a tube mounted coaxially within the telescope and having a larger-dia-metered forward portion and a flexible rearward portion which tapers rearwardly to a smaller diameter, the axes of the two portions inherently forming an obtuse angle prior to insertion of the tube in said body so that the flexible rearward portion must be stressed into substantial alignment with the forward portion in order to accomplish the insertion, after which the flexible rearward portion constantly tends to move against the body's wall; means for securing the larger-dia-metered forward portion of said tube with respect to the inner wall of said body with the line of sight of the telescope passing centrally through that tube portion, and means operable from outside the body for adjusting the radial position of the smaller-dia-metered rearward portion with respect to the axis of said body.

2. In a telescope comprising a tubular body and a reticle support therein, means for adjustably mounting said reticle support in operative position, comprising: a tube mounted within said body and extending axially thereof, said tube having a larger-dia-metered forward portion and a flexible rearward portion which tapers rearwardly to a smaller diameter, the axes of the two portions inherently forming an obtuse angle prior to insertion of the tube in said body so that the flexible rearward portion must be stressed into substantial alignment with the forward portion in order to accomplish the insertion, after which the flexible rearward portion constantly tends to move against the body's wall; means for securing the forward end of said tube with respect to the inner wall of the body; and means operable from outside said body for adjusting the position of said reticle support with respect to the axis of said body, and including a pair of threaded members extending through the body wall and disposed 90° apart radially of the body, the tube being adapted so that its rearward end continually tends to be biased along a direction approximately 45° between and into contact with the inner ends of the threaded members.

3. In a telescope comprising a tubular body and a reticle support therein, means for adjustably mounting said reticle support in operative position, comprising: a tube mounted within said body and extending axially thereof, said tube having a larger-dia-metered forward portion and a flexible rearward portion which tapers rearwardly to a smaller diameter, the axes of the two portions inherently forming an obtuse angle prior to insertion of the tube in said body so that the flexible rearward portion must be stressed into substantial alignment with the forward portion in order to accomplish the insertion, after

which the flexible rearward portion constantly tends to move against the body's wall; a flange radially projecting from the forward end of said tube and having a notch cut into the margin thereof; a shoulder extending from the inner body wall for contacting the rearward face of said flange to prevent axial movement of the tube rearwardly therewith; a ring clamp mounted in said body and adapted to be threaded and tightened

5 against the forward face of said flange to prevent forward axial movement of the tube, the said shoulder and flange serving securely to fix the reticle support tube against any axial movement; a member carried by said shoulder and protruding therefrom for engagement with the notch in said flange to register the tube's rotative position with respect to the telescope body and to prevent any relative rotation between the two parts; and means operable from outside the body for adjusting the position of said reticle support with respect to the axis of said body and including a pair of threaded members extending through the body wall and disposed 90° apart radially of the body, the tube being adapted so that its rearward end continually tends to be biased along a direction approximately 45° between and into contact with the inner ends of the threaded members.

4. Reticle supporting means for a telescope, comprising, a tube having a forward portion adapted to be secured within the telescope and a flexible rearward portion freely movable in all radial directions therein, the axes of the two portions inherently forming an obtuse angle prior to insertion of the tube in the telescope so that the flexible rearward portion must be stressed into substantial alignment with the forward portion in order to accomplish the insertion, after which the flexible rearward portion constantly tends to spring in a predetermined direction against the wall of the telescope.

5. The reticle supporting means of claim 4 in which the tube's rearward portion has a number of slots cut into a substantial part of its wall in order to facilitate its flexible nature and tendency to spring in a predetermined direction against the telescope's wall.
